UNITED STATES PATENT OFFICE

1,936,665

TAP HOLDER

Adelard J. Gauthier, Detroit, Mich., assignor to
 Packard Motor Car Company, Detroit, Mich., a
 corporation of Michigan

Application June 7, 1929. Serial No. 369,178

5 Claims. (Cl. 10—135)

This invention relates to tap holders, and more particularly to devices for holding taps for the multiple tapping of threads.

Heretofore, great difficulty has been experienced in the multiple tapping of threads where the taps are of different leads, and hence operate at different depths in a work piece. The stress and strain imposed upon taps when operating under such conditions results in either stripping 10 the threads or breaking the tap or both.

The fault lies in a positive engagement of the taps with the work piece and the uniform speed of operation thereof regardless of the variation in the leads of the taps. Then, too, a very serious objection has been found in that where, for any cause, any one of the taps in a group become chocked, it invariably snaps or breaks. It is the aim of the present invention to overcome these objections.

20 An object of the invention is to provide a tap holder for the multiple tapping of threads having different leads.

Another object of the invention is to provide a tap holder for the multiple tapping of threads 25 of different leads, having means providing the necessary pressure for starting the operation of the taps and compensating for the difference in the leads thereof.

Another object of the invention is to provide a 30 tap holder in which a spring furnishes the necessary pressure to start the tap and compensates for the depth in which the tap is operating in the work piece.

Another object of the invention is to provide a 35 tap holder designed to relieve stress and strain on the tap when in operation in a work piece and when being removed from the work piece.

A further object of the invention is to provide a 40 tap holder having a clutch adapted to be automatically thrown out when an excessive load is imposed upon the tap or when the tap becomes chocked.

A further object of the invention is to provide a 45 tap holder for the multiple tapping of threads of different leads without injury to the threads or to the taps.

Another feature of the invention is a tap holder 50 having telescopic parts and the spring associated therewith to furnish the necessary pressure for starting the taps and to compensate for the difference in the leads.

A further feature of the invention is a tap 55 holder comprising a clutch adapted to retain the parts in operative relation, until an excessive

load is imposed upon the tap, whereupon the parts become automatically disengaged.

Other objects of the invention will appear from the following description taken in connection with the accompanying drawing, which forms a part of this specification, and in which:

Figure 1 is a longitudinal sectional view of a tap holder embodying the invention.

Figure 2 is a cross sectional view taken substantially on line 2—2, Figure 1.

Figure 3 is a cross sectional view taken on line 3—3, Figure 1.

Figure 4 is a cross sectional view taken on line 4—4, Figure 1, and

Figure 5 is a fragmentary view of the end of the shaft illustrating the rollers for gripping the head of the tap.

Referring to the drawing for more specific details of the invention, 10 represents a body portion having formed integral therewith a shank 11 provided with the conventional square 12. As shown, the body portion 10 is provided with shouldered portions 13 and 14 and radial openings 15, the object of which will hereinafter appear. The body portion is axially bored as indicated at 16, and positioned in the bore for reciprocation is a plunger 17 actuated by a coil spring 18. The plunger has a head 19 substantially in the form of a cone.

A sleeve 20 is positioned for rotation on the shoulder 14, and formed in this sleeve to register with the radial openings 15 are recesses 21. As shown, balls 22 are positioned in the openings 15 and the registering recesses 21 and these balls are normally held in position by the plunger 17 to lock the sleeve 20 to the body portion 10. The sleeve 20 is provided with diametrically disposed slots 23—the object of which will hereinafter appear.

Positioned on the shoulder 13 is a sleeve 24. This sleeve provides a suitable housing for the sleeve 20 and serves to retain the sleeve 20 on the shoulder 14. The sleeve 24 is secured to the body portion by transverse pins, 25, and formed in the sleeve is a shoulder 26 engaging the sleeve 20 to retain it in position. The sleeve 24 is further provided with an inturned flange 27 and mounted for reciprocation in the sleeves 20 and 24 is a shaft 28. This shaft has formed thereon a shoulder 29 which provides a bearing for a washer 30, and diametrically positioned in the shaft are longitudinal slots 31 in which are suitable guide members or keys 32. These guide members provide an adequate bearing for a washer 33, and they engage the slots 31 in the sleeve 110

24. 05
 This sleeve provides a suitable housing for the sleeve 20 and serves to retain the sleeve 20 on the shoulder 14. The sleeve 24 is secured to the body portion by transverse pins, 25, and formed in the sleeve is a shoulder 26 engaging the sleeve 20 to retain it in position. The sleeve 24 is further provided with an inturned flange 27 and mounted for reciprocation in the sleeves 20 and 24 is a shaft 28. This shaft has formed thereon a shoulder 29 which provides a bearing for a washer 30, and diametrically positioned in the shaft are longitudinal slots 31 in which are suitable guide members or keys 32. These guide members provide an adequate bearing for a washer 33, and they engage the slots 31 in the sleeve 110

20 to prevent relative rotation between the sleeve and the shaft. Positioned intermediate the washers 30 and 33 on the shaft 28 is a coil spring 34, the objects of which will hereinafter appear.

5 Normally, the spring 34 retains the washer 30 against the shoulder 29 on the shaft 28 and the inturned flange 27 on the sleeve 24, also the washer 33 against the end of the sleeve 29 and the keys 32 in the shaft. It will be observed that 10 the spring 34 and its connections with the shaft provide for reciprocatory movement of the shaft, and retard the inward and outward movement thereof. The spring performs the function of a cushion for the shaft upon movement thereof in 15 either direction, and also furnishes the pressure necessary in starting the operation of the tap.

On the free end of the shaft is a clutch mechanism. As shown, the shaft is axially bored as indicated at 35, and the shaft has a diametrical slot 36 communicating with the bore. The stem 20 of a tap 37 fits snugly in the bore and the conventional square head 38 thereon engages the slot. Rollers 39 are mounted in the slot. These rollers are oppositely disposed and are adapted to engage the head 38. As shown, the rollers 39 have an axle 40 and are adapted to engage guide ways 41, adjacent to the slots 36. The shaft 23 is externally threaded as indicated at 42 and mounted to travel upon the thread is a sleeve or collar 43 the interior of which is conical, and threaded in the sleeve 43 is a collar 44 closely fitting the shaft. The sleeve 43 serves to press the rollers 39 in engagement with the square head 38 upon the stem of the tap.

35 Normally, the plunger 17 actuated by the spring 18 presses the conical shaped head 19 into point contact engagement with the balls 22 to lock the body of the holder to the sleeve 20 which is locked to the shaft 28 against relative rotation 40 by the keys 32. This structure insures the rotation of the body 10 and the shaft 28 concomitantly up to a predetermined load. When the predetermined load is reached, the torque imposed on the holder through the tap in the 45 work piece causes the balls 22 to move inwardly against the action of the spring pressed plunger 17 causing the plunger to retract, whereupon the balls 22 disengage the recesses 21 in the sleeve 20 and permit relative rotation between the head 50 and the sleeve. This immediately relieves any stress or strain on the tap.

Although the invention has been described in connection with certain specific embodiments, the principles involved are susceptible of numerous other applications, as will readily occur to persons skilled in the art. The invention is therefore to be limited only as indicated by the scope of the appended claims.

Having thus described the various features of my invention, what I claim as new and desire to secure by Letters Patent is:

1. A tool holder comprising a driving member, a driven member, an automatic clutch mechanism

positioned between the driving and driven members and provided with radially movable ball members engaging the driving and driven members, an axially movable tapered plug member in the driving member normally engaging each of the radially movable members at a single point, and spring means urging said plug axially in a direction to maintain the ball members in an engaging relation with the driving and driven members.

2. A tool holder comprising relatively movable parts, one of said parts having a chuck associated therewith, and an automatic clutch intermediate the parts including radially movable ball members engageable with the parts, an axially movable tapered plug member having point contact with each of the radially movable members, and spring means urging said plug axially in a direction to maintain the ball members in engaging relation with the parts.

3. A tool holder comprising a driving member having an axial bore and radial recesses therein in communication, a tapered plug in the axial bore, spring means for biasing the plug axially, a driven member having radial recesses adapted to register with the radial recesses of the driving member, and balls having point contact with the plug and normally held in the registered recesses by the plug to affect a driving connection between the driving and the driven members, but effective on over-loads to move the plug axially against the pressure of the spring means to allow the bodies to withdraw from the bores in one of the members to break the driving connection.

4. A tool holder comprising a driving member having an axial bore and radial recesses therein in communication with the bore, a spring pressed tapered plug in the axial bore, a driven member having radial recesses therein adapted to register with the radial recesses of the driving member, and spherical members normally held in the registered radial recesses of the driving and driven members by the spring pressed tapered plug to effect a driving connection between the driving and driven members, but effective on over-loads to move the plug axially to allow the spherical members to withdraw from the recesses in one of the members thereby breaking the driving connection.

5. A tool holder comprising a driving member having an axial bore and radial recesses in communication with the bore, a driven sleeve having radial recesses therein adapted to register with the recesses in the driving member, balls disposed in the registered radial recesses normally effective to establish a driving connection between the driving and the driven members, and a spring pressed tapered plug in the axial bore having a point contact with the balls, said plug being yieldable on over-loads to permit the balls to withdraw from the recesses in the sleeve to break the driving connection.

ADELARD J. GAUTHIER.
